CLOSING AND CLEANING ATTACHMENT FOR
EXTENSIBLE WINDOW SCREENS

Frank Siken, Baltimore, Md.

Application June 30, 1942, Serial No. 449,062

4 Claims. (Cl. 160—11)

This invention relates to window-screens, and especially to a closing and cleaning attachment for extensible window-screens.

One object of this invention is to overcome a defect in all extensible window-screens known to the inventor, viz., a defect that includes a number of openings through which large insects can pass from outside to inside a building in which the screen is installed.

Another object is to provide a practical and effective means by which the wire netting can be cleaned or brushed by the simple operation of alternately extending and collapsing the slidably interengaged frames of the screen.

Another object is to provide an attachment that effects both of the above-mentioned functions when properly attached and operated and which can be attached by any person of ordinary ability and without using any tool or device for doing so.

Other objects are pointed out or implied in the following details of description, in connection with the accompanying drawing in which:

Fig. 1 is a front elevation of an extensible window-screen having one of my closing and brushing attachments in its normal position and secured thereon.

Fig. 2 is a greatly enlarged fragmental sectional view, the section being taken at line 2—2 of Fig. 1.

Fig. 3 is a fragmental sectional view along the line 3—3 of Fig. 2, the normally upright or vertical elements being here disposed horizontally and being broken off at different distances from their ends for rendering parts of all the vertical elements visible.

Fig. 4 is a cross-sectional view of a modified form of brush and its attaching means, or spring-clasp and one of the frame-engaging longitudinal extensions that enter upper and lower slots in either one of the interengaged frames.

Fig. 5 is a fragmental sectional view showing one end portion of each of two attachments that include the modified form of brush and attaching means such as is shown in Fig. 4.

Referring to the drawing in detail: similar reference numerals refer to similar parts throughout the written description and in the several views of the drawing.

Though the two slidably interengaged screen-frames are substantial counterparts, and neither one is wholly inner or outer, the one having my attachment thereon in Figs. 1, 2 and 3, will be designated as the outer one, and the other one as the inner; the attachment being preferably

applied on the outer frame when not attached on both inner and outer frames, for if attached only on the inner side, insects could enter between the two sheets of wire netting and probably die therein. The description of one such attachment will suffice for each form of the invention; and it should be understood that two of such devices on an extensible window-screen are needed only for brushing both sheets of wire-netting, and not for closing insect-passages, one being sufficient.

Each one of the screen-frames includes upper and lower elements 10 that are longitudinally slotted at 11 to receive and contain the upper and lower edges of the wire-netting 12 and also to contain the ends of a normally vertical bar 13, the one at the right in Fig. 1 being partly covered by a lateral extension of a special form of brush that will be described later. As seen in Fig. 2, the bar 13 is composed of a sheet-metal strip that is folded over the adjacent edge of wire-netting and has its main intermediate part bent longitudinally in semblance of an angle beam whose flange 14 extends approximately to the wire-netting of the companion or interengaged screen-wire or wire-netting; but it is seen that this flange 14 does not extend to either the upper or lower frame-element 10, so there is a large opening 15 at each end of each vertical bar 13 through which can enter large flies, bees, beetles, etc. Moreover, it is well known that wire-netting in screens often sags or bulges, and where it bulges away from the vertical beam 13, insects can enter between the flange 14 and the thus-bulged portion of wire-netting.

My invention overcomes the foregoing defects by providing a brush that extends from the upper frame-element 10 to the lower frame-element 10 while it is fitted against the end-portions 16, but thereby spaced from the main intermediate portions or flanges 14, so a special form of brush-head or lateral extension is needed to completely close the openings referred to. The brush-head may be of sheet-metal, as at 17 (Figs. 1, 2, 3), or of wood or other appropriate material, as shown at 17a (Figs. 4, 5). These brush-heads are provided with lateral extensions 18 and 18a, respectively, that are of sheet metal in the form of a strip that normally overlies the space and joint between the brush-head and the nearby flange 14 and end-portions 16, such strip being of such length that it normally extends from the upper to the lower frame element 10, so it combines with the brush to effectively close the space and openings referred to;

for the bristles 19 of the brush are of proper length to extend to and through the wire netting, even where the latter is considerably bulged or sagged. The brush-head 17 may include a length of wire 17x extending longitudinally through the bristle-clamping part of the brush-head and beyond the latter at opposite ends to form frame-engaging elements that extend into the slots and combine with a hook or springy lateral extension 18x that can be caused to project through the wire netting and snap over the adjacent edge of the upright bar 13 and combine with other elements of the strip 18 or 18a to form a clasp that clamps or grips the adjoining upright bar 13.

In the form shown in Figs. 4 and 5, the strip 18a has end-extensions preferably (but not essentially) of the form shown at 180 where the strip has end-portions folded inward to double the thickness so as to more nearly conform to the width of the slot it is seated in; and each end-extension may be provided with one or more struck-up teeth or inclined spurs 181 the inclination being such that by a lateral movement of the vertical brush, its end-extensions can be slid into the ends of the slots and will be secured in normal position by the sharp ends or apexes of the teeth or detents 181.

It is to be understood that the wire-netting is shown conventionally, and so are the brush-bristles, and that the latter term is used in its broadest sense and does not confine the invention to animal bristles. Moreover the invention is not limited to the precise details described and shown, for it is susceptible of numerous changes within the scope of the inventive ideas as implied and claimed.

I claim the following as my invention:

1. In combination, two slidably inter-engaged and over-lapped window-screen-frames, each

filled with a sheet of wire-netting and each having a normally vertical bar that extends across the wire-netting of the adjoining window-screen-frame; and an attachment comprising the sub-combination of a brush having bristles substantially throughout its length and normally extending from top to bottom of the exposed part of either sheet of wire-netting, and means on said brush to secure the latter against the bar of either frame while its bristles extend toward and through portions of the wire-netting of the other frame, for purposes specified.

2. In the combination defined in claim 1, said means comprising a spring-clasp adapted to extend across and grip said vertical bar of either one of said screen-frames, and brush-end extensions adapted to engage with the upper and lower portions of the frame and to combine with said spring-clasp in attaching the brush with maximum stability.

3. The attachment defined in claim 1, said means comprising a strip of sheet-material united with said brush and having a lateral projection the same length of said brush and adapted to overlie and close any open space between said brush and adjoining bar and having thereon a hook for engagement with the side of the bar opposite to the side at which said brush is to be placed.

4. The attachment defined by claim 1, said means comprising a lateral projection united with the brush and terminating in a springy hook adapted to be snapped over the edge of said bar remote from said brush, said brush having end-extensions adapted to enter the upper and lower portions of said frame and to cooperate with said hook for effecting maximum stability of said brush with respect to said vertical bar.
